CLAIM

The ornamental design for a rotary insect deterrent, as shown and described.

DESCRIPTION

FIG. 1 is a top, rear, right side, perspective view of a rotary insect deterrent;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, front, right side perspective view thereof.

The broken lines shown in the drawings depict portions of the rotary insect deterrent that form no part of the claimed design. The unshaded area between solid and broken line structure forms no part of the claimed design.

1 Claim, 8 Drawing Sheets
